[57] CLAIM

The ornamental design for a hanging multiproduct dispenser, as shown and described.

DESCRIPTION

FIG. 1 is a front elevational view of a hanging multiproduct dispenser showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top, front perspective view thereof;

FIG. 8 is a top, rear perspective view thereof;

FIG. 9 is a vertical cross-sectional view thereof, taken along line 9—9 of FIG. 1;

FIG. 10 is a front elevational view of an alternate embodiment thereof;

FIG. 11 is a rear elevational view of the embodiment of FIG. 10;

FIG. 12 is a bottom plan view of the embodiment of FIG. 10; and

FIG. 13 is a top plan view of the embodiment of FIG. 10.
